DANIEL M. KUCHTA AND FRANK BALLOU, OF BROOKLYN, NEW YORK.

STRIKING-MACHINE.

1,366,192.

Specification of Letters Patent. Patented Jan. 18, 1921.

Application filed April 28, 1920. Serial No. 377,305.

To all whom it may concern:

Be it known that we, DANIEL M. KUCHTA and FRANK BALLOU, both citizens of the United States, residing at the borough of Brooklyn, city of New York, county of Kings, and State of New York, have invented certain new and useful Improvements in Striking-Machines, of which the following is a specification, reference being had therein to the accompanying drawings, which form a part thereof.

Our invention relates to striking machines, and more particularly to a type thereof in which compressed air is used as the medium for registering the force of the impact of a mallet or other implement with the anvil block.

In a machine made in accordance with our invention, we employ a registering mechanism capable of indicating the force of a blow upon a depressible anvil head, said mechanism being differentially operative through the medium of air pressure developed by the movement of a piston carrying said anvil head and mounted in a cylinder from which the air under a pressure determined by the force of a blow upon said head or the rapidity of the descent of the piston, is conveyed to the actuating means for said registering mechanism. In this manner it is possible to register the comparative force of different blows upon said anvil head with sufficient accuracy for the purpose of a machine which is designed for use merely as an amusement device, and not for determining, with any degree of scientific accuracy, the force of the blow delivered.

A machine made in accordance with our invention has the advantage that it possesses more or less mystery as to its mechanisms thus tending to arouse the curiosity of the public with a consequent incentive to its extensive use.

Striking machines heretofore extensively used have employed a structure somewhat of the nature of a catapult, in which a movable weight, slidably mounted upon a vertically extending wire, has movement with relation to a graduated vertical scale, the comparative force of succeeding blows being determined by observing the movement of the projectile, which descends sufficiently rapidly to prevent any accuracy in determining the effect of the blow.

In a device made in accordance with our

invention, there will be a slight dwell of the dial finger of the registering mechanism, and a more or less slow return to normal, so as to permit a more or less accurate reading of the dial.

Associated with the registering mechanism is a compressed air actuated gong so connected with the same source of power as operates the registering mechanism, as to cause the sounding thereof with each actuation of the machine and substantially simultaneously with the actuation of the registering mechanism.

While it is essential to provide restoring means for the piston so as to permit the automatic return of the various working parts to their normal positions, the construction and arrangement of parts is such that the registering and the gong mechanisms will be restored to normal through gravity, the air flowing to the cylinder upon the intake stroke of the piston momentarily retarding the return movement of the registering mechanism so as to permit the reading of the record as to the force of the blow struck.

The actuating means for the registering mechanism and for the gong are so constructed that these mechanisms will be responsive only to a sudden development of pressure, a gradual development of such pressure having substantially no operative effect upon these mechanisms.

We also provide means in each of the air lines from the cylinder to the dial finger actuating mechanism and the gong striker actuating mechanism, which will cause the development of the desired pressure in the cylinder and its effective application to said mechanisms, while permitting adjustment which will regulate the power applied to these mechanisms to secure the desired operative effect thereon.

The machine is so constructed that the registering mechanism will be but a short distance from the ground, thus bringing this mechanism sufficiently close to the user to add attractiveness to the character of the machine.

In conjunction with the registering mechanism, we provide a counter adapted to be actuated through the same agencies actuating the said mechanism, thus automatically recording the number of times the machine has been actuated and providing a positive check upon the earning of the machine, so

as to protect the owner thereof from possible pilfering.

The construction of the machine is so simple throughout, that it will not become disarranged from the hard use to which a machine of this character is subjected, while permitting an inexpensive production of the machine, and the use of standard fittings and equipment.

10 The invention consists primarily in a striking machine embodying therein a cylinder having a vertically extending bore, a piston mounted therein, a piston rod surrounded by an anvil head exteriorly of said cylinder and having a loose fit in the cylinder head, a registering mechanism consisting of a dial and a movable dial finger associated therewith, a pipe line leading from said cylinder and terminating adjacent said dial, a plunger cap slidably mounted upon the end of said pipe line adjacent said dial, and operative connections between said plunger cap and said dial finger, whereby the sudden development of pressure in said cylinder as a result of a blow upon said anvil head, and the resultant movement of said piston, will actuate said plunger cap and transmit movement to said dial finger proportionate to the pressure developed in said cylinder; and in such other novel features of construction and combination of parts as are hereinafter set forth and described, and more particularly pointed out in the claims hereto appended.

35 Referring to the drawings,

Figure 1 is a side view in vertical section of a machine made in accordance with our invention; and

40 Fig. 2 is a front view of the registering mechanism with the dial broken away and the front of the casing supporting same, removed, to disclose the detailed arrangement of the actuating means for said mechanism.

45 Like letters refer to like parts throughout both of said views.

In the embodiment of our invention shown in the drawings, we employ a platform *a* having at one end thereof a cylinder *b* having a vertical bore, and provided with 50 an upper head *b'* having a central bearing opening therein. Mounted in said cylinder is a piston *c*, the stem *c'* of which is provided with an anvil head *c''* preferably having a cushioned top of soft rubber to prevent the jarring of the user of the machine and avoid any substantial noise in its operation. The piston *c* is normally thrust upwardly by means of a coiled spring *d* within 55 the cylinder *b*.

60 Also mounted upon the platform *a* is a housing *e* having a hinged rear wall *e'* so as to permit ready access to the working parts within said housing. The upper part of this housing is circular and the front 65 thereof is closed by a dial face *e''* having any

desired arrangement of numbers thereon for indicating the force of a blow. Extending transversely of this enlarged head is a cross beam *f*. Pivotaly mounted between said cross beam *f* and the dial face *e''* is a pinion *g* carried by and rotatable with a shaft *f'*. Carried by said shaft is a dial finger *g'* disposed between the dial face *e''* and a light of glass *e'''* protecting the dial face and finger.

75 Leading from the bottom of the cylinder *b* is a pipe line *h* terminating below but adjacent the cross beam *f*, and opening inwardly of the casing *e*.

Slidably mounted upon the end of said pipe line and inclosing same for a sufficient distance to insure the desired extent of movement thereof, is a plunger cap *h'* actuating a rack *h''* meshing with the pinion *g*. In the form of the invention shown, this rack is a straight reciprocatory rack having movement in the guide way *f''* carried by the cross head *f*. Acting upon said rack is a spring *h'''* supplementing the action of gravity upon the cap *h'* in restoring said cap and the dial finger to normal after each actuation of the piston *c*. By properly proportioning the diameter of the pinion *g* and the length of movement of the plunger cap *h'*, any desired range in the operation of the 95 machine may be secured.

In order to have a check upon the operator of the machine, we mount an ordinary ratchet register *j* above the cap *h* with the actuating stem *h* thereof in the path of 100 movement of said cap, so that said register will be actuated with each upward movement of the cap as the result of the development of pressure in the cylinder *b* due to the force of a blow upon the anvil head *c''*.

105 In order to set the device to secure the desired extent of movement of the cap *h'* with the development of a given pressure in the cylinder *b*, I provide a pressure reducing valve *m* in the length of the pipe line *h* so as to permit the setting of the machine to secure any desired movement of the dial finger *g'* with a given pressure in said cylinder.

Also leading from the cylinder *b* is a second pipe line *n* extending vertically through 115 the casing *e* and terminating adjacent the top thereof. Surmounting the end of said pipe line is a plunger cap *n'* which serves as a striker member operative with relation to a gong *n''* preferably mounted above the 120 casing *e*, but in close proximity to the top thereof, the striker plunger cap *n'* being so closely mounted in relation to said gong as to insure the sounding of the latter with each down stroke of the piston *c*. In order to secure the desired operative effect of said striker plunger cap, I provide a pressure reducing valve *o* in the length of the pipe *n*.

The piston stem *c'* has a sufficiently loose fit in the bearing in the cylinder head *b'* to 130

avoid the development of a subatmospheric pressure above the piston with a resultant retardation in the descent of this piston when the head c^2 is struck with a mallet.

5 The operation of the herein described device is substantially as follows:—

The user of a machine made in accordance with our invention, strikes the anvil head c^2 with a wooden mallet, thus forcing the

10 piston c inwardly of the cylinder through the medium of the rod c and against the tension of the spring d and the resistance of the air cushion below said piston. While the spring d will resist the inward movement of 15 the piston, the development of the air pressure essential to the registering of the approximate force of the blow, is dependent upon the small capacity of the pipe line h alone or coupled with the reducing valve m .

20 The pressure thus developed will assist the spring d in cushioning the force of the blow, and in retarding the descent of the piston thereunder.

As the air under a pressure determined by 25 the force of the impact of the mallet with the anvil head c^2 or the skill in the use of the mallet, flows through the pipe line h it will force the plunger cap h' upwardly to an extent determined by the pressure of the 30 air. The upward movement of the plunger cap h' will carry with it the rack h^2 , which in turn will rotate the pinion g and its shaft f' , and thus actuate the dial finger g' in a manner to register the quantity of movement 35 of the cap h' .

Since this cap has a free sliding fit with the end of the pipe h , it is apparent that the instant the top of the cap moves away from the end of the pipe h , the air will vent freely 40 between the cap and the end of the pipe, and thus check a continued movement of said cap in excess of that resulting from the initial delivery of air within same, or permit only movement beyond that impelled by this 45 initial impact to that required to permit the reduction of air pressure in a degree which will prevent a continued movement.

The spring d will have a tendency to restore the piston c to its normal high position in the cylinder b immediately upon the piston reaching the limit of its downward movement under the impact of the mallet with the anvil head c^2 , which upward movement of said piston under the influence 50 of said spring will also have the effect of lowering the pressure of the air in the pipe line h and develop sub-atmospheric pressure within the cylinder which will be relieved by the admission of air through the open end of 55 the pipe line h .

The downward movement of the piston c will have a tendency to develop a subatmospheric pressure above same, which, however, will be relieved by air passing about the 60 bearing b' for the piston stem c' . The air

contained in the upper part of the cylinder b above the piston, will slightly retard the return upward movement of the piston, thus affording a slight dwell and a slow initial return of the piston to normal. This will result in a slight dwell of the dial finger g' which will enable the user to observe the force of the blow registered upon the dial face e^2 .

The upward movement of the rack h^2 will 70 be against the tension of the spring h^3 which will assist gravity in restoring the cap h' and rack h^2 to normal immediately following the limit of the upward movement of said parts.

As the cap h' ascends, it will engage the 75 stem h of the automatic counter j , and thus register each actuation of the machine.

The guide f^2 holds the rack h^2 in engagement with the pinion g .

Simultaneously with the flow of air under pressure through the pipe line h , air under the same pressure will flow through the pipe line n and thus impart a sudden rapid movement to the plunger cap n' , which will strike 90 and sound the gong n^2 . The pressure regulating valves m and o will not only retard the rapid flow of the air from the cylinder b and thus insure the application of a quick sudden impulse to the caps h' and n' , but 95 may also be used to set the device so as to insure the desired quantity of movement of the rack h^2 and of the cap n' .

By using separate pipe lines each with its own pressure regulating valve therein, the 100 operative effect of the two caps may be controlled, and if so desired, the valve o may be so set that the gong will be rung only when a certain predetermined pressure has been developed in the cylinder b .

It is not our intention to limit the invention to the precise details of construction shown in the accompanying drawings. It is apparent that while we have shown a straight reciprocating rack meshing with a 110 pinion operating the dial finger, other rack and pinion mechanisms may be substituted therefor, if so desired. The particular relation of parts within the casing e may also be varied, without departing from the spirit 115 and scope of the invention.

Having described the invention, what we claim as new and desire to have protected by Letters Patent, is:—

1. A striking machine embodying there- 120 in a cylinder having a vertically extending bore, a piston mounted therein, a piston rod surmounted by an anvil head exteriorly of said cylinder, a registering mechanism consisting of a dial and a movable dial finger 125 associated therewith, a pipe line leading from said cylinder and terminating adjacent said dial, a plunger cap slidably mounted upon the end of said pipe line adjacent said dial, and operative connections between said 130

plunger cap and said dial finger, whereby the sudden development of pressure in said cylinder as a result of a blow upon said anvil head, and the resultant movement of 5 said piston, will actuate said plunger cap and transmit movement to said dial finger proportionate to the pressure developed in said cylinder.

2. A striking machine embodying therein 10 a cylinder having a vertically extending bore, a piston mounted therein, a piston rod surmounted by an anvil head exteriorly of said cylinder, a registering mechanism consisting of a dial and a movable dial finger 15 associated therewith, a pipe line leading from said cylinder and terminating adjacent said dial, a pressure regulating valve arranged in the length of said pipe line, a plunger cap slidably mounted upon the end 20 of said pipe line adjacent said dial, and operative connections between said plunger cap and said dial finger, whereby the sudden development of pressure in said cylinder as a result of a blow upon said anvil 25 head, and the resultant movement of said piston, will actuate said plunger cap and transmit movement to said dial finger proportionate to the pressure developed in said cylinder.

3. A striking machine embodying therein 30 a cylinder having a vertically extending bore, a piston mounted therein, a piston rod surmounted by an anvil head exteriorly of said cylinder, a registering mechanism consisting of a dial and a movable dial finger 35 associated therewith, a pipe line leading from said cylinder and terminating adjacent said dial, a plunger cap slidably mounted upon the end of said pipe line adjacent said dial, a pinion connected with said dial finger, and a rack carried by and movable with said cap and meshing with said pinion, whereby the sudden development of pressure in said cylinder as a result of a blow 40 upon said anvil head, and the resultant movement of said piston, will actuate said plunger cap and transmit movement to said dial finger proportionate to the pressure developed in said cylinder.

4. A striking machine embodying therein 45 a cylinder having a vertically extending bore, a piston mounted therein, a piston rod surmounted by an anvil head exteriorly of said cylinder, a registering mechanism consisting of a dial and a movable dial finger 55 associated therewith, a pipe line leading from said cylinder and terminating adjacent said dial, a pressure regulating valve arranged in the length of said pipe line, a plunger cap slidably mounted upon the end 60 of said pipe line adjacent said dial, a pinion connected with said dial finger, and a rack carried by and movable with said cap and meshing with said pinion, whereby the sudden development of pressure in said cylinder 65

der as a result of a blow upon said anvil head, and the resultant movement of said piston, will actuate said plunger cap and transmit movement to said dial finger proportionate to the pressure developed in said 70 cylinder.

5. A striking machine embodying therein 75 a cylinder having a vertically extending bore, a piston mounted therein, a spring in said cylinder having a normal tendency to raise said piston, a piston rod surmounted by an anvil head exteriorly of said cylinder, a registering mechanism consisting of a dial and a movable dial finger associated therewith, a pipe line leading from said cylinder 80 and terminating adjacent said dial, a plunger cap slidably mounted upon the end of said pipe line adjacent said dial, and operative connections between said plunger cap and said dial finger, whereby the sudden 85 development of pressure in said cylinder as a result of a blow upon said anvil head, and the resultant movement of said piston, will actuate said plunger cap and transmit movement to said dial finger proportionate 90 to the pressure developed in said cylinder.

6. A striking machine embodying therein 95 a cylinder having a vertically extending bore, a piston mounted therein, a spring in said cylinder having a normal tendency to raise said piston, a piston rod surmounted by an anvil head exteriorly of said cylinder, a registering mechanism consisting of a dial and a movable dial finger associated therewith, a pipe line leading from said cylinder 100 and terminating adjacent said dial, a plunger cap slidably mounted upon the end of said pipe line adjacent said dial, a pinion connected with said dial finger, and a rack carried by and movable with said cap and meshing with said pinion, whereby the sudden 105 development of pressure in said cylinder as a result of a blow upon said anvil head, and the resultant movement of said piston, will actuate said plunger cap and transmit movement to said dial finger proportionate to the pressure developed in said cylinder.

7. A striking machine embodying therein 110 a cylinder having a vertically extending bore, a piston mounted therein, a spring in 115 said cylinder having a normal tendency to raise said piston, a piston rod surmounted by an anvil head exteriorly of said cylinder, a registering mechanism consisting of a dial and a movable dial finger associated therewith, a pipe line leading from said cylinder 120 and terminating adjacent said dial, a pressure regulating valve arranged in the length of said pipe line, a plunger cap slidably mounted upon the end of said pipe line 125 adjacent said dial, a pinion connected with said dial finger, and a rack carried by and movable with said cap and meshing with said pinion, whereby the sudden development of pressure in said cylinder as a re- 130

sult of a blow upon said anvil head, and the resultant movement of said piston, will actuate said plunger cap and transmit movement to said dial finger proportionate to the pressure developed in said cylinder.

8. A striking machine embodying therein a cylinder having a vertically extending bore, a piston mounted therein, a piston rod surmounted by an anvil head exteriorly of said cylinder, a registering mechanism consisting of a dial and a movable dial finger associated therewith, a pipe line leading from said cylinder and terminating adjacent said dial, a plunger cap slidably mounted upon the end of said pipe line adjacent said dial, a register mechanism having its actuating stem in the path of movement of said cap, and operative connections between said plunger cap and said dial finger, whereby the sudden development of pressure in said cylinder as a result of a blow upon said anvil head, and the resultant movement of said piston, will actuate said plunger cap and transmit movement to said dial finger proportionate to the pressure developed in said cylinder.

9. A striking machine embodying therein a cylinder having a vertically extending bore, a piston mounted therein, a piston rod surmounted by an anvil head exteriorly of said cylinder, a registering mechanism consisting of a dial and a movable dial finger associated therewith, a pipe line leading from said cylinder and terminating adjacent said dial, a plunger cap slidably mounted upon the end of said pipe line adjacent said dial, operative connections between said plunger cap and said dial finger, whereby the sudden development of pressure in said cylinder as a result of a blow upon said anvil head, and the resultant movement of said piston, will actuate said plunger cap and transmit movement to said dial finger proportionate to the pressure developed in said cylinder, a gong, a pipe line leading

from said cylinder and terminating adjacent said gong, and a plunger cap slidably mounted upon the end of said last named pipe line adjacent said gong, whereby the development of pressure in said cylinder will cause said last named cap to forcibly impact with said gong.

10. A striking machine embodying therein a cylinder having a vertically extending bore, a piston mounted therein, a piston rod surmounted by an anvil head exteriorly of said cylinder, a registering mechanism consisting of a dial and a movable dial finger associated therewith, a pipe line leading from said cylinder and terminating adjacent said dial, a plunger cap slidably mounted upon the end of said pipe line adjacent said dial, operative connections between said plunger cap and said dial finger, whereby the sudden development of pressure in said cylinder as a result of a blow upon said anvil head, and the resultant movement of said piston, will actuate said plunger cap and transmit movement to said dial finger proportionate to the pressure developed in said cylinder, a gong, a pipe line leading from said cylinder and terminating adjacent said gong, a plunger cap slidably mounted upon the end of said last named pipe line adjacent said gong, whereby the development of pressure in said cylinder will cause said last named cap to forcibly impact with said gong, and a pressure regulating valve arranged in the length of said last named pipe line.

In witness whereof we have hereunto affixed our signatures, in the presence of two subscribing witnesses, this 26th day of April, 1920.
